UNITED STATES PATENT OFFICE.

FREDERICK W. MOORE, OF NEW YORK, N. Y.

MACHINE FOR ORNAMENTING PLUSH AND SIMILAR MATERIALS.

1,294,516.

Specification of Letters Patent. Patented Feb. 18, 1919.

Application filed January 7, 1916. Serial No. 70,765.

To all whom it may concern:

Be it known that I, FREDERICK W. MOORE, a citizen of the United States, residing in the city, county, and State of New York, have invented a new and Improved Machine for Ornamenting Plush and Similar Materials, of which the following is a specification.

My invention relates to a machine used for ornamenting the surface of plush and similar materials by cutting away portions of the surface to produce the ornamentation thereon, and an object of my invention, among others, is to provide a machine of this kind in the use of which the ends of the fibers comprising the pile or nap may be neatly, rapidly and effectively cut away to produce an ornamented surface having designs of wide and varying character.

20 A machine, in the construction and use of which the objects herein set out, as well as others, may be attained, is illustrated in the accompanying drawings, in which—

Figure 1 is a perspective view of a portion of a machine embodying my invention.

Figs. 2 and 3 are detail views, scale enlarged, showing a section of my improved gage roll and a knife and their action upon the fibers in the operation of the machine.

30 Fig. 4 is a detail view showing a slightly different form of gage roll.

Fig. 5 is a perspective view of a portion of a machine showing a little different form of feed roll.

35 In carrying out my invention I employ a belt knife skiving machine of well known construction as to many of its parts, my invention contemplating such a construction of a roll in place of the gage roll that the fibers comprising the nap or pile of plush or similar material will be so distributed and supported as to permit an effective action of the cutting knife, this roll thus constituting a fiber distributing and supporting ledger

40 roll. In the place of the usual gage roll of machines of this class, my fiber distributing and supporting ledger roll has the pattern which I desire to produce on the material formed on the surface of such roll by cutting away portions thereof in such manner

50 that this pattern surface will cause the knife to produce a similarly depressed surface

upon the fabric operated upon, the depth and conformation of the depressions in the supporting roll being accurately calculated as the measure of the depth and conformation by which the cuts to be made in the material is determined.

A roll embodying my invention comprises part of the machine partially shown in the drawings herein in which the numeral 5 denotes the feed roll of a belt knife skiving machine, that rests against a bed roll 6 of rubber or similar material, although this bed roll may be in some instances composed of a comparatively hard material. The numeral 7 indicates spreading rolls supported in front of the feed roll in position to deliver a sheet of material into the throat between the feed roll and the fiber adjusting and supporting ledger roll 10. After passing through between said rolls the fabric may be led around a tension roll 11 from whence it may be delivered on to a reel 12. A knife 13 is supported with its edge between the fiber supporting and feed rolls, as shown in Fig. 1 of the drawings and in position to operate upon the material as it is delivered against it from between said rolls. The mechanism comprising the rolls hereinbefore mentioned except as to the fiber supporting roll, may be of any ordinary form and may be driven in any suitable manner, and being of old and well known construction a further and detailed description is omitted herein.

My invention has to do especially with the construction of the fiber distributing and supporting ledger roll 10 that is provided with depressions 14 of a depth having special reference to the length of the fibers comprising the pile or nap of the plush or other material to be operated upon or ornamented by use of the machine. In the ornamenting operation of the apparatus the fibers 15 that are engaged by the raised or outer feed surface 16 of the roll 10 will be bent or pressed downwardly toward the body of the fabric, and this will prevent the knife from taking hold of these fibers and they will, therefore, be uncut, and in the travel of the fabric between the rolls they will pass underneath the knife as shown in Fig. 3 of the drawings. The fibers 17, on the con-

trary, which are fed or moved opposite the depressions 14, will stand uncompressed and as the surface of the rolls approach each other they will rise freely and without restraint in a curvilinear position into the depressions, and the latter will be of such depth as compared with the length of the fibers that the ends of the latter will touch the bottoms of the depressions that act upon the fibers to hold them at the proper angle to the plane with respect to movement of the cutting knife, and this contact with the bottoms of the depressions will be such that the latter, together with the side surfaces of said depressions, will afford such frictional resistance to the bending movement of the fibers, as to enable the knife 13 to effectually take hold and cut off the ends of the fibers projecting into the depressed surfaces. By reason of the frictional hold and support of the bottom and side of the depressions against the ends of the fibers so that the knife will operate upon them I have termed such holding surface a friction super-surface. It is of the utmost importance that the depth of the depressions 14 be accurately determined to free the fibers from compression and the friction super-surface be, therefore, accurately positioned, as if such friction super-surface be too far from the feed surface of the roll, except on narrow and small spaces the fibers will either be supported not at all, or to such a slight extent as to enable them to give way and bend in front of the cutting knife, whereas, on the contrary, if these friction super-surfaces be too near the feed surfaces of the roll then the fibers will be bent over to such an extent that the knife will either not take hold, as the fibers will be bent downward toward the body of the fabric and passed underneath the knife in a manner similar to that above described with respect to the fibers 15 which are located against the raised or feed portions of the outer surface of the roll, or else the hold of the knife will be so uncertain that the fibers will be cut unevenly, some passing underneath the knife without being cut and others being cut of uneven lengths.

In the construction of the friction super-surfaces as shown in Fig. 4 such surfaces 18 are roughened in any suitable manner to increase the frictional hold of these surfaces upon the ends of the fibers.

As an aid in supporting the fiber supporting roll 10 and preventing its springing action, when such roll is of extreme length, I may employ a saddle which is commonly used in machines of this class, or I prefer to use a fiber supporting roll rest roll 22 rotatably mounted in the lower edge of machine frame plates 23 and pressing against and supporting the fiber supporting roll intermediate its ends.

In the form of apparatus illustrated in

Fig. 1, a sectional feed roll 5, composed of rings on a loose shaft resting on a bed roll 6 and regulated by ring plates 9 and of a size and so arranged that they coöperate with the feeding surface on the roll 10, is made use of, the object being to arrange rings to engage the feeding surface only of the roll 10 and to act only in connection with such surface and thus permit an unrestricted action of that portion of the roll comprising the friction super-surface. This arrangement is more particularly adapted to the production of straight line effects in the ornamented surface.

In the form of apparatus shown in Fig. 5 the feed roll comprises a solid roll 24 which is in fact a supporting roll for the fabric, it being understood that the feed roll in my improved machine does not exert any undue pressure upon the fabric nor more than is required to support the fabric and insure its movement against the surfaces of the fiber supporting roll with a pressure sufficient to feed the material uniformly against the friction super-surface and to the knife and to obtain this result the upper and lower feed rolls 5 and 10 shown in Fig. 1 should turn at the same speed. If in the operation of the machine upon material of a comparatively light weight it shall be found that the friction drive usual in the ring roll feeding device as shown in Fig. 1 is not sufficient to control and turn each individual ring at the required speed, then the lower feed roll may be a solid roll constructed to be the equivalent of the ring roll driven by positive drive to turn at the same speed as the fiber supporting roll and as shown in Fig. 5 of the drawings.

I have found that the best results are obtained with as little pressure as possible between the feed roll and the distributing and ledger supporting roll, this pressure in fact being just sufficient to move the fabric along and this movement will be obtained with the rolls at such distance apart that the uncut fibers will be depressed to the same extent substantially as the length to be cut from the other fibers.

It is equally important that the fibers to be cut shall rise freely and without restraint into the recesses provided for their reception, as if they are compressed or forced into the depressions and are caused to assume an abnormal position, the cutting will be very irregular and unsightly. When thus positioned in the depressions they must be supported as a ledger blade supports a shear to permit the knife to readily cut off the ends and this support may be effected in at least two ways. When the depressions into which the fibers rise are of such a width that the ends of the fibers will all be located within each depression at the time that the knife first contacts with the fibers in

that depression, a sufficient support will be afforded by the fibers against each other and against the rear wall of the depressions, the term "rear" being used with respect to the 5 direction of movement of the surfaces of the roll toward the knife. When, however, the depressions are of such width that the knife will come into contact with the front edge of the mass in a depression before the ends 10 of the fibers are all located in that depression then other means of support are provided, in such case the bottoms of the depressions being accurately located so that the ends of the fibers will rise against the 15 bottoms and be thus supported and without distortion.

It will thus be seen that the back walls of the depressions act after the manner of a ledger blade in a cutting machine, the 20 ledger blade element, however, being movable instead of stationary, this ledger blade action consisting in a carrying of the fibers, by the rear walls of the depressions toward and against the knife, that does the cutting 25 and I have, therefore, used this term ledger roll in the specification herein to describe the supporting roll having such action, and in which roll the fibers, in their natural and unrestrained state are led in an upright position 30 against the knife and are all supported during the action of the knife.

While I have shown and described herein a satisfactory construction of mechanism for accomplishing my purpose, this may be departed from to a greater or lesser degree and yet be within the spirit and intent of the 35 invention.

I claim—

1. In a machine of the character described, 40 a cutting device, a fiber supporting roll with surfaces in design, one of which surfaces comprises projections to depress portions of the pile to cause them to pass below the cutting edge of the knife, the end surfaces of 45 said projections constituting a feed surface, and another of said surfaces of which is depressed to constitute a supersupporting surface, to frictionally contact with the end portion of the fibers comprising the pile to 50 retain said fibers in a substantially uncompressed and erect condition while being cut, and means for supporting the fabric while being cut, said supporting means coacting with the feed surface of the fiber supporting 55 roll to feed said fabric, uncompressed by separating from it as it is passing the knife.

2. In a machine of the character described, 60 a cutting device, a fiber supporting roll with surfaces in design, one of which surfaces comprises projections to depress portions of the pile to cause them to pass below the cutting edge of the knife, the end surfaces of 65 said projections constituting a feed surface, and another of said surfaces of which is depressed and which is roughened to constitute

a supersupporting surface to frictionally contact with the ends of a portion of the fibers comprising the pile, to retain said fibers in a substantially uncompressed and erect condition while being cut, and means 70 for supporting the fabric while being cut, said supporting means coacting with the feed surface of the fiber supporting roll to feed said fabric.

3. In a machine of the character described, 75 a cutting device, a fiber supporting roll with dual surfaces in design formation, one of which surfaces comprises projections to depress portions of the pile to cause them to pass below the cutting edge of the knife, and 80 another of said surfaces of which is depressed to constitute a supersupporting surface, and a feeding member arranged to cooperate with said roll and spaced therefrom to hold a portion of the fibers against the 85 ends of the projections without material compression to cause feed of the fiber, said spacing also permitting other portions of the fibers to rise in the depressions and to be supported therein in uncompressed condition. 90

4. In a machine of the character described, a cutting device, a fiber supporting roll with surfaces in design, one of said surfaces constituting the periphery of the roll and the 95 feed surface thereof, and another of said surfaces comprising the bottoms of depressions which are roughened to constitute a frictional supporting surface, and a feeding member spaced from said supporting roll 100 sufficiently to depress a portion of the fibers below the cutting edge of the knife and without material compression, such spacing being merely sufficient to cause proper feeding of the material and also to permit other 105 portions of the fibers to rise into the depressions and be supported by the bottoms thereof without material compression.

5. In a machine of the character described, a cutting device, a fiber supporting roll having dual surfaces, one of which constitutes the periphery of the roll and comprises a feed surface and the other of which comprises the bottoms of depressions spaced from the feed surface sufficiently to receive 115 a portion of the fibers undistorted, but to support and lead them against the cutting device, and a feeding member spaced from said roll to support the fabric with a portion of the fibers compressed merely sufficient 120 to cause proper feed of the fabric, said spacing also permitting the action of the fibers within the depressions as hereinbefore mentioned.

6. In a machine of the character described, 125 a cutting device, a fiber supporting roll comprising a feed surface spaced from a supersurface to eliminate pressure from the supersurface, the latter comprising a friction surface above the feed surface to act 130

upon the ends of the fibers and support them
uncompressed to a material degree and lead
them against a cutting device, and a sup-
porting member spaced from said roll suffi-
5 ciently to compress a portion of the fibers
without material compression but sufficiently
for feed purposes only and to permit the

action of said supersurfaces in the manner
hereinbefore described.
